CLAIM

I claim the ornamental design for a tool assembly, as shown and described herein.

DESCRIPTION

FIG. 1 illustrates a front perspective view of the tool assembly;

FIG. 2 illustrates a front elevation view of the tool assembly of FIG. 1;

FIG. 3 illustrates a rear elevation view of the tool assembly of FIG. 1;

FIG. 4 illustrates a top view of the tool assembly of FIG. 1;

FIG. 5 illustrates a bottom view of the tool assembly of FIG. 1;

FIG. 6 illustrates a left side elevation view of the tool assembly of FIG. 1; and,

FIG. 7 illustrates a right side elevation view of the tool assembly of FIG. 1.
